ANNUNCIATOR

Hugo Panissidi, Jamaica, N. Y., assignor to International Business Machines Corporation, New York, N. Y., a corporation of New York

Application August 12, 1942, Serial No. 454,482

7 Claims. (Cl. 177—327)

The improved annunciator comprising the present invention is primarily designed for use in connection with telemetering systems of the type shown and described in a U. S. Patent of Ward Leathers, No. 2,314,720, dated March 23, 1943, for Automatic meter reading apparatus. The invention, however, is capable of a wide variety of uses and the same may, with or without modification, be employed in the conventional type of annunciator systems used in hospitals, apartment houses, schools, offices and the like. The device is also adaptable for use in rendering stock quotations or in connection with score boards, signaling systems and the like. Irrespective, however, of the particular uses to which the invention may be put, the essential features of the same are at all times preserved.

Heretofore, annunciator systems have been devised wherein a series of indicators, having various indicia printed or otherwise marked thereon, are projected across an opening in a casing for visual observation. Because of the difficulty encountered in projecting a large number of these indicators into position in the same plane, many annunciator systems employ a large number of openings or windows each associated with a single character or indicia. Where attempts have been made to selectively project all of the indicia-carrying members across a single opening in the annunciator casing, the projection has not been uniform and the indicators move into position in different planes. Where the system utilizes a lens through which the indicators are viewed, the net result has been that only those indicators which are projected across the opening in close proximity to the lens become visible in a sharp and distinct manner. Those indicators which are projected across the opening at a distance from the lens ordinarily appear blurred and the effect is not satisfactory. The present invention is designed to overcome the above noted limitations that are attendant upon annunciator systems of this character, and, toward this end, the same contemplates the provision of an annunciator system having a plurality of movable pivoted indicia-carrying members, which are conveniently grouped in an inoperative concealed position adjacent the viewing opening of the annunciator casing and which may selectively be projected across the opening for the purpose of being viewed, all of the members moving into position across the opening in a common plane or arc, whereby they are held in close proximity to the opening and to the lens which is mounted therein, thus assuring that

each and every indicating member will be distinctly and sharply seen through the lens.

This being the principal object of the invention, another object thereof is to provide an annunciator system which is magnetically operated and which employs a minimum number of actuating magnets.

In carrying out this last mentioned object, the invention provides for a permutation bar system utilizing four permutation bars each having slots therein and the slot thereof being adapted upon shifting of the bars to move into alignment in such a manner as to provide clearance for movement of the various indicia-actuating members. Inasmuch as the present invention is illustrated in connection with the displaying of the ten Arabic numerals from 0 to 9 inclusive, the use of at least four permutation bars is required, this being the minimum number of bars possible. Thus, for shifting the bars, only four operating magnets are required and the invention distinguishes from other annunciator systems utilizing ten or more magnets in this regard. Obviously, where a larger number of indicia are to be displayed, the number of permutation bars and magnets employed will be increased.

It is a still further object of the invention to provide an apparatus of the character set forth above in which the mechanism required to shift the permutation bars and project the indicia-bearing members into visible position is extremely small, thus permitting the use of relatively small magnets and, consequently, decreasing the weight and size of the apparatus. In other words, it is an object of the present invention to provide an apparatus of this character which is extremely compact and not bulky.

A further object of the invention is to provide an annunciator apparatus in which the various character-bearing elements are selectively movable from a retracted position to a projected position in a uniform manner and without side play, thus insuring accurate alignment of the characters with the viewing opening through which they become visible.

Another object of the invention is to provide an annunciator system having movable indicia-carrying elements, the movements of which are controlled by a series of permutation bars and the permutation bars being capable of applying a relatively large traveling movement to the indicia-carrying elements, while at the same time these bars move throughout a very small distance themselves.

Yet another object of the invention is to pro-

vide an apparatus of this type in which there is no lost motion of the various parts, so that the character-bearing elements may be projected into position rapidly and with a minimum of effort.

Another object of the invention is to provide an apparatus which is rugged and durable and which consequently is unlikely to get out of order.

With these and many other objects in view, which will become more readily apparent as the nature of the invention is better understood, the same consists in the novel constructions and arrangements shown in the accompanying two sheets of drawings, in which

Fig. 1 is a side elevational view of an annunciator constructed according to the principles of the present invention. In this view a portion of the annunciator casing has been broken away to more clearly reveal the nature of the invention.

Fig. 2 is a sectional view taken substantially along the line 2-2 of Fig. 1.

Fig. 3 is an enlarged fragmentary side elevational view of annunciator display assembly per se.

Fig. 4 is a sectional view taken substantially along the line 4-4 of Fig. 3.

Fig. 5 is a diagrammatic view of the electrical connections for the annunciator system.

Fig. 6 is a schematic view of the permutation system employed for obtaining the selected code employed in connection with the invention.

Fig. 7 is a perspective view of a permutation beam and link employed in connection with the present invention.

In all of the above described views, like characters of reference are employed to designate like parts throughout.

Referring now to the drawings in detail, the apparatus involves in its general organization a casing 10, including a base plate 12, front and rear walls 14 and 16 respectively, side walls 18 and 20, and a top wall 22. The front wall 14 is formed with an inclined portion 24 having a window or opening 26 therein in which there is disposed a viewing lens 28, which is preferably of a magnifying nature.

A character display assembly 30 is mounted directly behind the viewing opening 26, and this assembly is adapted to be actuated in a selective manner by a permutation bar assembly 32, which is, in turn, actuated by means of a magnet group or assembly 34, the magnets of which are adapted to be selectively controlled by a more or less conventional coding unit 36 (see Fig. 5). This latter unit 36 includes a series of coding magnets of the relay type which are capable of being selectively energized under the control of a conventional keyboard 38. The specific nature of the coding apparatus 36 has not been illustrated. However, reference may be had to an application for U. S. Patent of Ward Leathers, Serial No. 349,975, filed August 2, 1940, for Automatic meter reading apparatus, for a full and complete description of the operation of this device.

The character display assembly includes a series of substantially vertically disposed upper U-shaped frame-like supporting members 40 and a similar series of lower inclined members 42, the outer ends of all the members being pivotally mounted on a horizontal shaft 43, the ends of which are anchored in the opposite side walls 18 and 20 of the casing 10. Each of the members 40 and 42 carries on its base portion a flex-

ible, transparent, indicia-bearing member 44, which may be in the form of a substantially rectangular strip of Celluloid or other artificial celulose material, or a transparent, flexible, resinous material upon which there is suitably printed, painted or otherwise marked the desired characters to be displayed through the opening 26.

While any suitable member of indicia-bearing members may be employed and while any desired indicia may be carried thereby, for illustrative purposes ten such members are shown and each carries thereon one of the ten Arabic numerals from 0 to 9 inclusive.

15 The members 44 normally occupy retracted positions wherein they are grouped or stacked, so to speak, on either side of the viewing opening 26 in two groups of five each and are adapted upon pivotal swinging movement of the members

20 40 and 42 to be selectively projected into a position immediately behind the lens 28 wherein they are individually visible from outside of the casing. A pair of guide brackets 46 are secured to the inside of the inclined portion 24 of the casing 10 and are formed with arcuate guide portions 48, which receive the side edges of the members 44 and guide members into close proximity to the lens 28 when the members are projected in the casing 10.

30 A light source 50 may be mounted intermediate the two brackets 46 and behind the same in the casing in order that light issuing therefrom will illuminate the indicia and cause the same to become plainly visible through the lens 28.

35 Each of the U-shaped members 40 and 42 is formed with attachment ears 52, to which at offset or eccentric points there is pivoted one of a series of ten operating bars or thrust rods, including five such rods 54 which are pivoted at 40 their forward ends to the upper U-shaped members 40 and five additional rods 56 pivoted to the lower U-shaped members 42. The rear ends of the various thrust rods 54 and 56 are pivotally connected to respective operating arms 58 and 60, which latter arms are integrally formed with pear-shaped tumbler bars 62 and 63, each provided with trunnions 64, by means of which they are supported between the two side walls 18 and 20 of the casing 10, at upper and lower levels 50 respectively.

45 A vertical strut 66 extends upwardly in the casing 10 in the forward regions thereof and is anchored to the base plate 12 and upper wall 22, and a similar strut 68 is provided in the casing 55 in the rear regions thereof. A series of tension coil springs 70 are anchored to the forward strut 66 and to the various rods 54, while a similar series of springs 72 are connected between the strut 66 and the rods 56. The springs 70 and 72 serve to normally and yieldingly hold the rods 54 and 56 in such positions that the various indicia-carrying members 44 are in their retracted positions.

50 A series of permutation bars 74, 76, 78 and 80 have their ends slidably disposed in and are supported from the two struts 66 and 68 and project between the upper and lower series of tumbler bars 62 and 63. The permutation bars are formed with a plurality of notches 82 in the upper edges thereof (see Fig. 6) and with a similar series of notches 84 in the lower edges thereof. The upper notches 82, as well as the lower notches 84, are so located in the various permutation bars that when all of the bars are 75 in their extreme rear position within the casing

10 (i. e. the extreme right hand position as viewed in Fig. 1), no alignment of notches transversely across the group of bars is attained, but alignment will be attained whenever at least one of the bars is shifted to its extreme forward (or left hand) position.

As stated above, the Telelector system of coding is preferably employed in the present instance. This core is essentially a four line code and its specific nature may be understood by reference to U. S. Patent to Ward Leathers and Archibald Gold, dated March 23, 1943, No. 2,314,718, for Automatic meter reading apparatus.

While the various indicia-bearing members 44 may be arranged in a single group or stack, it has been found convenient to arrange the same in two groups in order to conserve space. For convenience of illustration, the characters 0, 9, 4, 8 and 3 have been assigned to the lower group, and the characters 7, 2, 6, 1 and 5 have been included in the upper group, and the code or permutation bars 14, 76, 78 and 80 have been provided with upper and lower notches according to this code. The pear-shaped tumbler bars 62 normally bear against the upper edges of the permutation bars and are adapted to be selectively projected into any of the notches 82 which happen to move into transverse alignment upon shifting of the bars. Similarly, the tumbler bars 63 normally bear against the lower edges of the permutation bars and are adapted to be selectively projected into any of the notches 84 which happen to move into transverse alignment when the bars are shifted according to the selected code.

The permutation bars 14, 76, 78 and 80 are free to shift in either direction. For moving the bars from their normal positions wherein the various notches are all out of alignment, a plurality of rocker arms 90, one for each bar, are pivoted to respective lugs 82 mounted on the rear strut 63. Each rocker arm carries an armature 94 and each armature is associated with an electromagnet, the various electromagnets being designated at 96, 98, 100 and 102 (see Fig. 5), one for each of the permutation bars 14, 76, 78 and 80 respectively. The various magnets just described are mounted on a common bracket 103 suitably supported in the casing 10. Each permutation bar includes a pin 104 adjacent its rear end and a series of fingers 106, formed on a rocker arm 103, serve to simultaneously restore such of the permutation bars as may from time to time become shifted to their forward positions during normal operation of the apparatus. The rocker arm 103 is controlled by an electromagnet 110 mounted on a bracket 112 suitably supported within the casing 10.

Referring now to Fig. 5, the various magnets 96, 98, 100 and 102 have been illustrated as being controlled through the coding device 36 from a keyboard designated generally at 38 and including ten character keys and an additional key, by means of which the magnet 110 is directly controlled by a by-pass circuit leading past the coding device. The specific coding device is employed is immaterial to the present invention and no claim is made herein to any novelty associated therewith. Any form of coding device which is suitable for closing the proper circuits leading to the magnets 96, 98, 100, 102 and 110 to secure proper operation of the indicia-carrying members 44 may be employed. If desired, the coding device 36, together with its cir-

cuits, may be omitted and a keyboard having four character keys one for each bar-actuating magnet and one key for controlling the permutation bar return magnet substituted for the keyboard 38. In such an instance, the operator would be required to become familiar with the specific code employed and would operate the various keys accordingly, making mental code computations at the same time.

10 It is to be noted that very slight shifting movement of the permutation bars is required to secure alignment of the various notches in the upper and lower edges thereof. Furthermore, inasmuch as the various notches themselves are 15 relatively shallow, the tumbler bars 62 do not move through a large angle, nor do the upper and lower thrust rods 54 and 56 have to move to any great extent before the various U-shaped members 40 and 42 will become fully actuated 20 and the indicia-carrying members 44 will become projected into position in alignment with the lens 28. Because of this fact, a very rapid projection of the members is obtained and also a rapid and almost instantaneous withdrawal 25 thereof is made possible.

The invention is not to be limited to the exact arrangement of parts shown in the accompanying drawings as various changes are contemplated within the spirit of the accompanying claims.

30 What is claimed is:

1. In an annunciator, a casing having an opening therein, a plurality of movable flexible indicators, means for supporting said indicators in stacked relationship adjacent one side of said opening and for selectively projecting the indicators into a position directly behind said opening, and stationary means positioned behind the opening for guiding each indicating member into substantially the same fixed position when said member is projected behind the opening.

40 2. In an annunciator, a casing having an opening therein, a plurality of supports mounted for pivotal movement about a common axis, a flexible indicating member mounted upon each support and movable therewith throughout an arc from a retracted position wherein it is concealed within the casing to a projected position wherein it is visible through the opening, and stationary means positioned in the path of said members for deflecting the same into substantially the same position of registry with the opening.

45 3. In an annunciator, a casing having an opening therein, a plurality of U-shaped supports pivotally mounted for rotation about a common axis which is parallel to the base portion of said supports, said members being selectively movable from retracted positions wherein the base portions of said supports overlie each other in close proximity to advanced positions, a flexible indicating member secured to the base portion of each support adjacent one edge of the former and projecting laterally from the support in such a manner that said members overlie each other in substantial stacked relationship when the supporting members are in their retracted positions, said indicating members being adapted upon movement of their respective supporting members to move throughout an arc to a position

50 wherein each is visible through said opening, and stationary means positioned in the path of movement of said members for flexing the same into substantially the same position of registry with said opening.

55 4. In an annunciator, a casing having an open-

ing therein, a plurality of indicating members mounted for pivotal movement about an axis and movable from retracted positions wherein they are concealed at one side of the opening to projected positions wherein they are in registry with said opening, a plurality of longitudinally shiftable permutation bars arranged in substantial parallelism and having notches formed in the sides thereof, said bars being of lesser number than the number of indicating members employed, said bars being individually movable from positions wherein the notches are out of transverse alignment to positions wherein certain of the notches are in transverse alignment completely across the bars, a tumbler bar for each indicating member bearing against said permutation bars and adapted to selectively enter the aligned notches of said bars when the latter are shifted, means operatively connecting the tumbler bars and indicating members for actuating the latter upon shifting of the bars, and means for selectively shifting said permutation bars.

5. In an annunciator, a casing having an opening therein, a plurality of indicating members mounted for pivotal movement about an axis and movable from retracted positions wherein they are concealed at one side of the opening to projected positions wherein they are in register with said opening, a plurality of longitudinally shiftable permutation bars arranged in substantial parallelism and having notches formed on the upper sides thereof, said bars being of lesser number than the number of indicating members employed, said bars being individually movable from positions wherein the notches are out of alignment to positions wherein certain of the notches are in transverse alignment completely across the bars, a tumbler bar for each indicating member mounted for pivotal movement about an axis in a plane above the upper surfaces of said permutation bars, said tumbler bars having eccentric portions resting upon and bearing against the upper surfaces of said bars and adapted to selectively enter the alignment notches of said bars when the latter are shifted, a linkage system connecting said tumbler bars to their respective indicating members for actuating the latter upon movement of said tumbler bars and means for shifting said bars.

6. In an annunciator, a casing having an opening therein, a plurality of indicating members mounted for pivotal movement about an axis and movable from retracted positions wherein they are concealed at one side of the opening to projected positions wherein they are in register with said opening, a plurality of longitudinally shiftable permutation bars arranged in substantial parallelism and having notches formed on the upper sides thereof, said bars being of lesser number than the number of indicating members

employed, said bars being individually movable from positions wherein the notches are out of alignment to positions wherein certain of the notches are in transverse alignment completely across the bars, a tumbler bar for each indicating member mounted for pivotal movement about an axis in a plane above the upper surfaces of said permutation bars, said tumbler bars having eccentric portions resting upon and bearing against the upper surfaces of said bars and adapted to selectively enter the aligned notches of said bars when the latter are shifted, a linkage system connecting said tumbler bars to their respective indicating members for actuating the latter upon movement of said tumbler bars, a rocker arm for each permutation bar having a follower operable upon movement of the arm to engage the bar and shift the same laterally, an electromagnet controlling the movement of each rocker arm, and a keyboard including electric circuits for energizing said electromagnets.

7. In an annunciator, a casing having an opening therein, a plurality of indicating members mounted for pivotal movement about an axis and movable from retracted positions wherein they are concealed at one side of the opening to projected positions wherein they are in register with said opening, a plurality of longitudinally shiftable permutation bars arranged in substantial parallelism and having notches formed on the upper sides thereof, said bars being of lesser number than the number of indicating members employed, said bars being individually movable from positions wherein the notches are out of alignment to positions wherein certain of the notches are in transverse alignment completely across the bars, a tumbler bar for each indicating member mounted for pivotal movement about an axis in a plane above the upper surfaces of said permutation bars, said tumbler bars having eccentric portions resting upon and bearing against the upper surfaces of said bars and adapted to selectively enter the aligned notches of said bars when the latter are shifted, a linkage system connecting said tumbler bars to their respective indicating members for actuating the latter upon movement of said tumbler bars, a rocker arm for each permutation bar having a follower operable upon movement of the arm to engage the bar and shift the same laterally, an electromagnet controlling the movement of each rocker arm, an additional rocker arm common to all of the permutation bars and adapted upon rocking movement thereof to bear against said bars and shift the same in the opposite direction in unison, an electromagnet for actuating said latter rocker arm, and a keyboard including electric circuits for energizing said electromagnets.
